CONDENSER

Felix Gerth, Berlin-Tempelhof, Germany, assignor to C. Lorenz Aktiengesellschaft, Berlin-Tempelhof, Germany, a company

Application October 4, 1935, Serial No. 43,480
In Germany October 6, 1934

1 Claim. (Cl. 175—41.5)

Ceramic materials have recently become known which owing to their small phase—or angle—difference and their high dielectric constant are particularly well adapted for use with condensers as the dielectric thereof. Such materials, however, in order to prove satisfactory require the condensers to be given special forms. In particular, if the customary condensers are in a simple manner fitted with intermediate layers of ceramic material, the requisite high breakdown voltages are difficult to obtain, because in this case a rigid material and air constitute the dielectric.

Therefore by the invention a construction of condensers is proposed which is adapted to obviate the formation of air cavities and thus avoids breakdown phenomena. A variable condenser according to the invention has ceramic plates which are ground onto each other and are at their outer surfaces provided with the metal coatings.

One embodiment of the invention is illustrated in the accompanying drawing in which Fig. 1 is an end view, Fig. 2 a sectional view of the condenser.

This condenser has two circular plates 1, 2 of ceramic material, which are provided with axles 3, 4 and are at their surfaces 7 ground onto each other, so that as in the case of adhesion plates no air cavities are between them. By means of the axles 3, 4 the plates 1, 2 can be turned with respect to each other, the condenser being adjustable in this way. The metal coatings 5, 6 are disposed on the outer faces of the plates to cover these faces partially. They are in a manner customary with circular plate condensers fixed on the plates 1, 2 by melting, or are electro-deposited on a layer that in its turn is produced on the plates 1, 2 by a melting process.

Since at 7 ceramic material is grinding on a material likewise ceramic, the plates 1, 2 are not likely to wear away when turned with respect to each other, so that air cavities are not likely to be formed.

The metal coatings 5, 6 are contained in excavations 8 of the plates 1, 2, and the edges of

these excavations 8 of the plates 1, 2, and the edges of these excavations are turned inward in the manner appearing from Fig. 2, so as to form a sort of torus 9 at the edge of each coating 5 and 6. These toruses act to avoid glow discharges and corona discharges as well as the well known sparking over, and above all do away with any breakdown phenomena. The electric strength thus created is active at any point of the edge of the coatings since these are completely encircled by the toruses 9.

Condensers having ceramic plates adapted to be turned in relation to one another are known per se but are of simple construction, being intended for relatively small potentials such as those dealt with in broadcast receivers. The object in the case of these known condensers is not to adapt them for great voltages, and none of them have plates ground onto each other or torus-shaped edge portions encircling the metal coatings.

The invention is intended for use with condensers of any configuration.

What is claimed is:

A variable condenser adapted to withstand high potential differences comprising two ceramic bodies disposed in close contact with each other, the portions of said bodies which are in contact with each other being closely fitted so as to substantially eliminate cavities between said bodies, means for rotating said bodies with respect to one another comprising a separate spindle for each plate, each of said spindles terminating at a point short of the contacting surfaces of said bodies, two metallic coatings one on each of said ceramic bodies disposed essentially parallel with each other, the space between said coatings being wholly filled with the ceramic material which constitutes the two bodies and said ceramic material extending beyond the edges of said coatings so that the shortest electrostatic path between said coatings which extends wholly or partially through air is many times as long as the shortest path which extends through the ceramic material.
